UNITED STATES PATENT OFFICE.

ANTHONY N. MARKERT, OF SYRACUSE, NEW YORK, ASSIGNOR TO WILL & BAUMER COMPANY, OF SYRACUSE, NEW YORK, A CORPORATION OF NEW YORK.

CANDLE-HOLDER.

1,054,973.

Specification of Letters Patent.

Patented Mar. 4, 1913.

Application filed May 7, 1912. Serial No. 695,700.

To all whom it may concern:

Be it known that I, ANTHONY N. MARKERT, of Syracuse, in the county of Onondaga, in the State of New York, have invented new and useful Improvements in Candle-Holders, of which the following, taken in connection with the accompanying drawings, is a full, clear, and exact description.

10 This invention relates to improvements in candle holders and applies more particularly to means for providing a neat and cleanly support for altar candles and vigil lights.

15 Heretofore it has been customary to support candles within hollow uprights provided with a spring in the base thereof for forcing the candle gradually upward in the stem. The melting wax ran down over the 20 body of the standard very often dripping upon the altar or the floor and presented a very disagreeable appearance as well as damaging the altar cloths and carpets and some labor was necessary to remove the wax.

25 My object, therefore, is to avoid these defects by providing a glass or jar to receive a candle or molten wax to form a candle in combination with means for supporting the same, so that the melting wax will 30 be retained in the jar until consumed.

A second object is to utilize the whole of the wax rather than a portion of the same by retaining it subject at all times to the action of the burning wick.

35 Having the above objects and uses in mind, my invention therefore consists in the several new and novel features of construction hereinafter described, in connection with the accompanying drawings which 40 form a part thereof.

Figure 1 is a side view of a candle holder embodying my invention. Fig. 2 is a cross section on line 1—1, Fig. 1. Fig. 3 is a side view of the base supporting the wax retaining jar and having the top portion broken away. Fig. 4 is a view of the wax retaining jar. Fig. 5 is a view of the wax or candle removed from the jar and showing a perforated plate on the bottom thereof.

—1— is a hollow upright having a sheet 50 metal lining —2— within the top of which is adapted to fit the circumferential flange —3— upon the base —4— to hold these parts together. The base —4— is shown with two upwardly extending arms —6— placed diametrically from each other and supporting a cap —7— having a circular opening in the top thereof for the passage of the flame.

55 A wax or candle containing receptacle —5— is adapted to pass between the arms —6— and rest upon the base —4— being retained therein by an upwardly extending circumferential flange —8—, upon the base —4—, and the arms —6—. This receptacle —5— is adapted to receive a candle —9— 60 as shown in Fig. 5 or molten wax may be poured into the receptacle and allowed to harden around the wick —10— therein to 65 form a candle.

70 There is attached to the bottom of the candle a disk of metal —11— to prevent the wax from sticking to the bottom of the receptacle —5—, portions of this disk being cut away upon three sides and bent upward upon the remaining attached side and adapted to be embedded in the candle to firmly 75 fasten the disk thereto as best shown in Fig.

2. This is preferably accomplished by placing a disk of this formation in the bottom of the candle mold and pouring the 80 molten wax thereon and allowing it to harden in this position, or the disk —11— may be placed in the bottom of the receptacle —6— and the candle placed upon it, the melting wax serving to attach it firmly 85 thereto.

Upon the bottom of the upright —1— is a cap —12— having a downwardly extending circumferential flange —13— with openings —14— therein. This flange —13— is 90 adapted to pass over a support for the candle holder and attach it thereto in an upright position.

What I claim is:

95 A candle holder comprising a hollow upright having means upon the base thereof for attaching it to a standard, a horizontal base plate having a downwardly extending

flange adapted to enter the hollow upright, and an upwardly extending flange having upwardly extending arms attached thereto, said arms connected at their upper end, and 5 a candle receptacle upon said base and between said arms.

In witness whereof I have hereunto set my hand on this 26th day of April 1912.

ANTHONY N. MARKERT.
